UNITED STATES PATENT OFFICE.

CHARLES J. AHRENFELDT, OF NEW YORK, N. Y.

DESIGN FOR A CHOCOLATE-JUG.

SPECIFICATION forming part of Design No. 24,199, dated April 16, 1895.

Application filed November 17, 1894. Serial No. 529,193. Term of patent 7 years.

To all whom it may concern:

Be it known that I, CHARLES J. AHREN-FELDT, a citizen of the United States, residing at New York, county and State of New York, 5 have invented a new and original Design for a Chocolate-Jug, of which the following is a specification.

In the accompanying drawings, Figure 1, represents a perspective view of a chocolate 10 jug embodying my design. Fig. 2 is a plan view of the top of the cover.

The essential feature of my design consists in an arabesque and escaloped ornamentation arranged upon the ware, substantially as 15 shown in the drawings.

Upon the lower portion of the jug a double row of escaloped ornamentation is arranged in such a manner that one row laps over the other. The upper edge of this escaloped ornamentation is formed in a series of groups each group separated from the other by a series of 20 segmental lines or depressions. These segmental lines extend above the escaloped ornamentation and all except three of these 25 segmentations merge gradually into the plain exterior surface of the jug. The escaloped ornamentation is sharply outlined on its upper edges. Below this sharply defined upper edge, the escalops grow less defined as they 30 run downward, and are deflected from a vertical line in a curve. They terminate in a ring shaped foot, which constitutes the base of the jug. The three segmental lines that do not merge into the plain exterior surface 35 of the ware extend in curved lines from the top to the bottom of the jug, and being deeply depressed cause the jug to assume a trefoil shape. This is especially pronounced at the top.

40 The handle of the jug is formed of a composite of arabesque and escaloped ornamen-

tation. The bottom terminates where it is attached to the body of the jug in an arabesque ornamentation. At this point the handle is turned or twisted laterally to heighten the 45 ornamental effect.

A series of arabesque ornamentations are lodged on the upper part of each one of the three segments into which the body of the jug is divided by the three greater segmental lines. This arabesque ornamentation is formed of series of curved lines, and extends about half way down the body of the jug, beginning a short distance below the lip of the jug. 55

The spout of the jug is ornamented with an escaloped ornamentation, which is pronounced on its upper edge and merges into the plain exterior on its lower portion.

The cover of the jug is segmented by three 60 lines and is ornamented on its surface with an escaloped ornamentation in a double row, which extends irregularly around the outer edge of the cover. The central portion of the top of the cover has a knob with an arabesque 65 ornament upon it.

In the drawings, A A is the double escaloped ornamentation; A', the groups of escalops. B is the arabesque. C is the trefoil shaped lip. D is the greater segmental lines. 70 D' is the lesser segmental lines. E is the handle. E' is the ornamental twisted end of the handle. F is the plain exterior surface, and G is the spout of the jug.

I claim—

75 The design for a chocolate jug, substantially as herein shown and described.

CHARLES J. AHRENFELDT.
